Primary Examiner—Stella Reid*Assistant Examiner*—Eric Watterson*Attorney, Agent, or Firm*—Browdy and Neimark[57] **CLAIM**

The ornamental design for a "faucet", as shown and described.

DESCRIPTION

FIG. 1 is a perspective view of a faucet showing my new design;

FIG. 2 is a front view thereof;

FIG. 3 is a rear view thereof;

FIG. 4 is a left side view thereof, the right side view is identical;

FIG. 5 is a top view thereof; and,

FIG. 6 is a bottom view thereof.

The broken line showing of the faucet handles are for illustrative purposes only and forms no part of the claimed design.
